UNITED STATES PATENT OFFICE.

PATRICK D. SKAHEN, OF SYRACUSE, NEW YORK.

CORNER CONSTRUCTION FOR BURIAL-CASES.

1,193,723.

Specification of Letters Patent.

Patented Aug. 8, 1916.

Original application filed February 20, 1907, Serial No. 358,497. Divided and this application filed July 25, 1912. Serial No. 711,457.

To all whom it may concern:

Be it known that I, PATRICK D. SKAHEN, of Syracuse, in the county of Onondaga and State of New York, have invented a new and useful Corner Construction for Burial-Cases, of which the following is a specification.

This invention has for its object the production of a corner construction for burial cases which is particularly simple in construction, economical of manufacture, and highly efficient and durable in use; and it consists in the combinations and constructions hereinafter set forth and claimed.

In describing this invention reference is had to the accompanying drawing in which like characters designate corresponding parts in all the views.

Figure 1 is an elevation of a burial case embodying my invention. Fig. 2 is a fragmentary view of a corner thereof. Fig. 3 is a section through the corner thereof.

My corner construction for burial cases comprises, generally, a hollow corner post having an intermediate body portion and lengthwise marginal flanges, the latter being arranged to interlock in reversely arranged grooves at the contiguous edges of two of the walls of the burial case, the body portion of the corner post between the bases of the flanges being arranged to receive the strain from the contiguous edges of the two walls and hold said two walls and the corner post from lateral movement.

1 and 2 designate, respectively, two walls of the burial case, which walls are arranged to form a corner, such walls being usually side and end walls.

In the illustrated form of my invention, the walls 1 and 2 are formed of sheet metal and are provided at their contiguous ends with outwardly-turned marginal flanges 3 bent in reverse directions into positions opposed to the major parts of the walls 1, 2 respectively, and thereby forming reversely arranged grooves.

4 designates the corner posts for joining the walls 1, 2 forming the corner, each corner post being formed of sheet metal bent to form an intermediate body portion 5 and in-turned flanges 6 extending lengthwise thereof and arranged to enter the grooves formed by the flanges 3, by an endwise sliding movement of the corner post.

The body portion 5 when in position is 55 spaced apart from the flanges 3 of the walls 1, 2 and engages on opposite sides of its median line, as at 7, with the walls 1, 2 at the bases of the flanges 3.

Preferably the walls 1, 2 engage each other 60 as at 8, and hence as the body portion 5 of the corner post is bowed outwardly and engages said walls as at 7, said walls are firmly held from lateral movement by each other by the body portion of the corner post, without the use of additional fastening means.

The walls 1, 2 are also usually formed with marginal flanges 9 along their upper and lower edges, the flanges being provided with interleaved flaps as 10, arranged to lap the 70 upper and lower ends of the corner post after the same has been moved into operative position by an endwise sliding movement.

This application is a division of my pending application Sr. No. 358,497, filed Feb. 20, 1907.

What I claim is:

1. A burial case having each of the meeting ends of two of its walls provided with 80 an external groove, the grooves being reversely-arranged, and a hollow corner post formed of sheet metal and having an intermediate body portion and lengthwise marginal flanges, the latter being interlocked in 85 the grooves, the body portion of the hollow corner post between the bases of the flanges being bowed outwardly and engaging with the end edges of said two walls near the median line of the corner post, substantially 90 as and for the purpose specified.

2. A burial case having each of the meeting ends of two of its walls provided with an external groove, the grooves being reversely-arranged, and a hollow corner post formed 95 of sheet metal and having an intermediate body portion and lengthwise marginal flanges, the latter being interlocked in the grooves, the body portion of the hollow corner post between the bases of the flanges 100 being bowed outwardly and engaging with the end edges of said two walls on opposite sides of the median line of said post for holding the side walls connected by the post from endwise movement, substantially as 105 and for the purpose set forth.

3. A burial case having each of the contiguous edges of two of its walls provided

with an external groove, said grooves being reversely-arranged and said walls engaging each other along their contiguous edges, and a hollow corner post having an intermediate body portion and lengthwise marginal flanges, the latter being interlocked in the grooves, the body portion between the flanges being bowed outwardly and spaced apart from said walls, and engaging the end edges 10 of said walls between the flanges of the corner post for holding the walls connected by the corner posts engaged with each other

and from endwise movement, substantially as and for the purpose described.

In testimony whereof, I have hereunto 15 signed my name, in the presence of two attesting witnesses, at Syracuse, in the county of Onondaga, in the State of New York, this 2nd day of July, 1912.

PATRICK D. SKAHEN.
